LOW-TENSION SPARKING PLUG FOR INTERNAL COMBUSTION ENGINES

Lucien Péras, Billancourt, France, assignor to Regie Nationale des Usines Renault, Billancourt, France

Application January 2, 1957, Serial No. 632,089

Claims priority, application France January 12, 1956

8 Claims. (Cl. 313—131)

It is well-known to technicians that sparking plugs for internal combustion engines have been developed in which the sparks are produced by discharging the current delivered from a condenser across a relatively reduced gap of from 0.004" to 0.012" between the two electrodes. This gap is filled by a mass of insulating material and the spark glances off its surface.

Generally, the assembly comprising the electrodes and the insulator is called "insert" or "cartridge."

This invention relates to low-tension sparking plugs and more particularly to improvements in the aforesaid inserts for sparking plugs of this character.

These inserts are characterized in that they consist of two metal electrodes in the form of coaxial hollow cylindrical members, the interval between these cylinders being kept to a constant value by an insulating cylinder filling without clearance the gap between the electrodes. A central hole is provided in the insulator for the dual purpose of permitting the assembling of the insert components by clamping and feeding the current to one of the electrodes.

According to another feature of this invention, the sparking surfaces of the cylindrical members, which are slanted lie consequently at the desired distance or space from each other are so machined, before or after the assembling step, that they diverge radially so that the space between the electrodes is splayed outwardly.

Sparkling plugs having this specific configuration, in accordance with the invention, are characterized by a long useful life and operate regularly. They are also advantageous in that they avoid completely the frequent drawback of low-tension sparking plugs whereby the spark, subsequent to a certain deterioration of the insulator, occurs inside the insert and does not ignite the air-fuel mixture.

In the accompanying drawings:

Figure 1 is an axial section showing a first embodiment of a sparking plug insert constructed in accordance with the teachings of this invention;

Figure 2 is a similar view showing a preferred method of assembling the component elements of the device of Fig. 1; and

Figures 3 and 4 are axial sections showing modified embodiments of the invention.

In the drawing, Figure 1 illustrates, by way of example, a typical embodiment of the invention wherein the electrode 1 is connected to the distributor through the central rod 2; the other electrode 3 is earthed through the sparking plug body (not shown) in which it is force fitted or otherwise secured. It will be understood that the electrodes may be cylindrical or may have a plurality of flat peripheral surfaces, as for example, they may be prismatic. The insulator 4 fills completely the inner space of the two superposed but spaced electrodes, and the sparks occur only on the massive portion 5 thereof.

As illustrated, the registering edges of the two cylinders are bevelled to form a gap splayed outwards, so that

the spark will occur on the free lateral surface of the insulator 4.

This insulator may consist, for example, of borosilicated glass according to the embodiments later herein described.

In a specific embodiment, it is possible for example, as illustrated in Fig. 2, to position the lower electrode 1 into a hollow cylinder 6 of refractory steel, with a certain clearance therebetween, and subsequently introduce 10 the upper electrode 3 for example after having interposed between the electrodes three detachable mica segments 7. The assembling step is completed by an upper cylinder 8 and a core 9 of refractory steel or graphite. Then the two electrodes 1, 3 are filled with glass powder, for example borosilicated glass, and the assembly is heated to about 1,470° F., whereafter the glass is compacted by exerting a certain pressure thereon by means of the piston 9. Upon cooling, the insulating material sets and finally the insert is ejected, and any glass having been extruded 20 in the sparking gap beyond the insulator surface is removed by a proper grinding operation. It will be understood that the mica pieces 7 may be left on or can be removed from the assembled electrodes as desired. These mica segments or pieces 7 are of a dimension that does not interfere with the sparking zone of the assembled electrodes.

Another possible embodiment of the present invention is illustrated in Fig. 3 of the drawing wherein the insulator 10 of the insert consists of a cylindrical body which 30 may be moulded beforehand and accurately machined to size; the upper electrode is formed with an inner shoulder 11 permitting an arcuate relative spacing of the two electrodes.

As an alternative, the narrowest portion of the spark 35 gap is not defined by the inner cylindrical surface of the electrodes but lies at an intermediate distance between this surface and the outer cylindrical surface of the electrodes. This modification is illustrated in Fig. 4. If the insulator consists of a sintered mixture of glass 40 and mica, the insulator may coincide with the narrowest portion of the spark gap by coating the lateral surface of the insulator body with powdered glass or lead silicoborate, or one of these powders in suspension in a liquid. Then the assembling step is performed during which the powder or paste fills the space 12, and finally the assembly 45 is subjected to a curing step to bind the auxiliary glass.

I claim:

1. In a low tension surface discharged spark plug, a hollow tubular first electrode, a second electrode spaced axially of the first electrode, an insulator core disposed axially in the first electrode and substantially corresponding in diametral dimensions to the bore thereof and extending axially out of one end thereof, the second electrode being adapted to receive the end of the insulator core extending axially from the first electrode, said electrodes having registering slanted, sparking, end surfaces spaced axially of each other and diverging radially of the electrodes in a direction away from the longitudinal axis of the first electrode thereby defining a splayed sparking zone, whereby the insulator maintains the electrodes spaced in a fixed axial relationship.
2. In a low tension surface discharge spark plug according to claim 1, in which the core insulator comprises a sintered glass and mica mixture.
3. In a low tension surface discharge spark plug according to claim 1, in which the electrodes are made of tungsten.
4. In a low tension surface discharge spark plug according to claim 1, in which the insulator core comprises borosilicated glass.
5. In a low tension surface discharge spark plug, a first hollow tubular electrode, a second electrode spaced

axially of the first electrode, an insulator core disposed axially in the first electrode and extending axially out of one end thereof, the second electrode being adapted to receive the end of the insulator core extending axially from the first electrode, said electrodes having registering slanted, sparking, end surfaces spaced axially of each other and diverging radially of the electrodes in a direction away from the longitudinal axis of the first electrode thereby defining a splayed sparking zone, and the core insulator having peripherally exposed surfaces in the space between the slanted surfaces of the two electrodes thereby to maintain the two electrodes axially spaced in fixed relationship.

6. In a low tension surface discharge spark plug, a first hollow tubular electrode, a second electrode spaced axially of the first electrode, an insulator core disposed axially in the first electrode and extending axially out of one end thereof, the second electrode being adapted to receive the end of the insulator core extending axially from the first electrode, said electrodes having registering slanted, sparking, end surfaces spaced axially of each other and diverging radially of the electrodes in a direction away from the longitudinal axis of the first electrode thereby defining a splayed sparking zone, and non-conductive means disposed in the space between the slanted surfaces of the two electrodes and having an outer diameter larger than the inner diameter of the first electrode and said outer diameter being smaller than the outer diameter of the first electrode.

7. In a low tension surface discharge spark plug, a hollow tubular first electrode, a second electrode spaced axially of the first electrode, an insulator core disposed axially in the first electrode substantially corresponding with the bore thereof and extending axially out of one end thereof, the second electrode being adapted to receive the end of the insulator core extending axially from the first electrode, said electrodes having registering slanted, sparking, end surfaces spaced axially of each other and diverging radially of the electrodes in a direction away from the longitudinal axis of the first electrode thereby

defining a splayed sparking zone, and the core insulator having a portion having an outer diameter larger than the inner diameter of the first electrode and said outer diameter being smaller than the outer diameter of the first electrode in the space between the slanted surfaces of the two electrodes.

8. In a low tension surface discharge spark plug, in combination, a hollow tubular first electrode, a second electrode disposed in axially spaced relation of the first electrode, an insulator core disposed axially in the first electrode and extending axially out of one end thereof, the second electrode being adapted to receive the end of the insulator core extending axially from the first electrode thereby to hold the two electrodes in axially spaced relationship, said electrodes having corresponding end, sparking surfaces disposed in juxtaposition axially of each other, said end surfaces of each of the electrodes being V-shaped and each having the apex thereof disposed toward each other, and constituting the point at which there is the least axial distance between the end surfaces, and the core insulator having a portion extending radially into the space defined between said end surfaces of the electrodes, said core portion having a diameter corresponding substantially to the diameter of the electrodes between two points wherein the axial distance between the electrodes is defined by the apex of said V-shaped surfaces, whereby a splayed sparking zone is defined between the electrodes and erosion of said core portion does not impede the discharge between said end sparking surfaces at least until the core is eroded to an extent wherein the diameter of said core portion corresponds to the inner diameter of said first electrode.
